UNITED STATES PATENT OFFICE

108,688

DESIGN FOR A DRESS

Samuel Zahn, New York, N. Y.

Application January 6, 1938, Serial No. 74,123

Term of patent 3½ years

To all whom it may concern:

Be it known that I, Samuel Zahn, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the specific lace trimmed pleats arranged on the blouse section as shown.

I claim:

The ornamental design for a dress, substantially as shown, and described.

SAMUEL ZAHN.
